UNITED STATES PATENT OFFICE.

FRANK HARDART AND JOHN ANDERSON, OF PHILADELPHIA,
PENNSYLVANIA.

CUTTER FOR BUTTER, &c.

SPECIFICATION forming part of Letters Patent No. 655,486, dated August 7, 1900.

Application filed March 16, 1900. Serial No. 8,894. (No model.)

To all whom it may concern:

Be it known that we, FRANK HARDART and JOHN ANDERSON, citizens of the United States, residing in the city and county of Philadelphia, in the State of Pennsylvania, have invented a new and useful Improvement in Cutters for Butter, &c., which improvement is fully set forth in the following specification and accompanying drawings.

10 Our invention consists of an improvement in a cutter for butter or any other suitable material, the same being adapted to feed the material uniformly and evenly, the means employed being herein set forth.

15 It further consists of novel details of construction, all as will be hereinafter set forth.

Figure 1 represents a perspective view of a cutter embodying our invention. Fig. 2 represents a side elevation of a portion of 20 the cutter. Fig. 3 represents a sectional view on line *x x*, Fig. 1, on an enlarged scale.

Similar letters of reference indicate corresponding parts in the figures.

Referring to the drawings, A designates a 25 cutter having a clamping device B for securing the said cutter to a suitable support, said clamping device carrying the bed C, the latter having the frame D at one end, to which are secured the dividing wires, cords, or bars E.

30 F designates a shaft which is mounted on the journals G and H, suitably supported and carrying on one end thereof the crank-arm J, provided with the cutter K, the same consisting of a taut wire extending between the 35 ends of said crank-arm. The other end of said shaft carries the head or wheel L, which has the cam M, the latter being adjusted by a screw N. The cam M consists of a flexible plate secured to the wheel L at one end, its 40 other end being free and engaged by said screw N.

P designates a traveler consisting of a rod guided in the ways Q and R and having on one end thereof the plate or follower S.

45 T designates a plate or disk loosely mounted on said traveler P between the stops Q and R and is normally held in position by a spring U, said plate T being guided by a pin V and said traveler P being further guided and

locked, if desired, by a set-screw W, one end 50 of which is adapted to enter a groove Z in the said traveler P.

The operation is as follows: The material to be cut is placed against the plate S on the bed C and the crank-arm J is operated, causing the rotation of the shaft F and the head or wheel L, which latter in turning causes the cam M to strike the plate or disk T, as indicated in Fig. 2, forcing an edge of the opening thereof against the traveler P, causing the same to bite and moving said traveler a certain distance and forcing the material to be cut against the wires E, so that a predetermined portion of said material is placed in the path of the cutter K, which now 60 operates to sever the parts, which can be directed into a proper receptacle. As soon as the cam passes the plate T the latter will be forced back into the position seen in Fig. 1 by the spring U and the parts will be ready for 65 the next operation, it being seen that by this means the traveler P is caused to move forward a certain distance by each revolution of the wheel L, and that said traveler can be quickly moved back, since said disk does not 70 engage the same until operated. It will be seen that the cam M can be adjusted by the screw N, so as to give the traveler P a desired throw. Mounted in an eye or ear B' on the way R is the rod or skewer A', the same 75 having a head A² and passing through the plate S, it being adapted to pierce the material to be cut. In operation the rod A' is drawn back by the head A², which stands normally in the position shown in Fig. 3, said 80 head being turned outwardly when it is desired to withdraw the rod or skewer A'. After the material is placed on the bed C the skewer is pushed forwardly by the head A², the skewer sliding through the eye B' and passing 85 again through the opening in the plate S to pierce the material, and thus firmly holding the same, so that it will not turn, while permitting the movement of the material toward the knives or cutting members. The 90 skewer remains stationary while the plate S moves forward.

It will of course be evident that if desired

the wheel L may be provided with additional cams and various changes may be made in the construction without departing from the spirit of our invention.

5 Having thus described our invention, what we claim as new, and desire to secure by Letters Patent, is—

1. In a cutter, a bed, a cutting device, a follower provided with a rearwardly-extending rod rigid therewith, a vibratory clutch-plate for said rod, stops between which said clutch-plate is confined, whereby it is prevented from moving beyond the stops with the follower and rod, said clutch-plate being normally disengaged from said rod, and means for simultaneously operating said cutting device for vibrating said clutch-plate between its stops to cause the clutch-plate to alternately engage said rod and advance the same.
- 10 2. In a cutter, a bed, a cutting device, a rod provided with a follower mounted upon said bed, a clutch-plate for said rod, a spring for holding said clutch-plate normally disengaged from said rod, and means for simultaneously operating said cutting device and for moving said clutch-plate against the action of said

spring into engagement with said rod and for advancing the same.

3. In a cutter, a bed, a cutting device, a rod provided with a follower mounted upon said bed, a movable clutch-plate, a spring for holding said clutch-plate normally out of engagement with said rod, a cam adapted to engage said clutch-plate and move the same against the action of said spring and into engagement with said rod and for advancing the same, and means for simultaneously operating said cutting device and said cam.

4. In a cutter, a bed, a cutting device, a follower mounted upon said bed, means for operating said cutting device and follower, said follower being provided with an aperture and a longitudinally-movable skewer mounted upon the frame of the machine and extending through said aperture, said skewer being adapted to be withdrawn and inserted longitudinally.

FRANK HARDART.
JOHN ANDERSON.
